CLAIM

The ornamental design for a gun cocking device, as shown and described.

DESCRIPTION

FIG. 1 is a perspective view of the gun cocking device showing my design in use with a gun;

FIG. 2 is another perspective view of the gun cocking device showing my new design;

FIG. 3 is a top view thereof;

FIG. 4 is a bottom view thereof;

FIG. 5 is a front view thereof;

FIG. 6 is a rear view thereof;

FIG. 7 is a side view thereof; and,

FIG. 8 is an opposite side view thereof.

The broken lines in the drawings are used to illustrate portions of the gun cocking device and environment that form no part of the claimed design.

1 Claim, 4 Drawing Sheets
